UNITED STATES PATENT OFFICE

THOMAS R. MOORE, OF WALDEN, NEW YORK.

EXPLOSIVE AND OTHER ENGINE.

986,021.

Specification of Letters Patent. Patented Mar. 7, 1911.

Application filed April 4, 1908. Serial No. 425,100.

To all whom it may concern:

Be it known that I, THOMAS R. MOORE, a citizen of the United States, and a resident of Walden, in the county of Orange and State of New York, have invented certain new and useful Improvements in Explosive and other Engines, of which the following is a specification.

The invention relates to improvements in internal-explosion and other engines; and it consists in the novel features, arrangements and combinations of parts hereinafter described, and particularly pointed out in the claims.

The object of my invention is to provide a novel, efficient and comparatively inexpensive engine, comprising a shaft, a fly-wheel or frame thereon having a polygonal opening in a part thereof defining a plurality of equal sides (as an illustration, four) a set of cylinders stationary within the vertical plane of said opening, and a set of pistons in said cylinders and connected at their outer ends in a slidable manner to the edge walls of said opening, with proper inlet and exhaust ports. During the operation of the engine two opposite pistons will move outwardly under the force of an explosion to drive the fly-wheel frame and shaft, while at the same time two other opposite pistons will be drawn outwardly by the rotating frame to draw in a charge of explosive mixture, all the pistons moving outwardly together and inwardly together, and said frame when its opening has four equal sides receiving four impulses during each of its rotations. During the inward movement of the pistons two opposite ones thereof discharge the burned gases from their cylinders, while two other opposite ones thereof compress the charge of explosive mixture in their cylinders preparatory to ignition.

The invention will be fully understood from the detailed description hereinafter presented, reference being had to the accompanying drawings, in which:

Figure 1 is a central vertical longitudinal section of an engine constructed in accordance with and embodying the invention; Fig. 2 is a vertical transverse section of the same on the dotted line 2—2 of Fig. 1; Fig. 2 shows the rotary power-transmitting frame as having made a one-eighth rotation from its position shown in Fig. 1; Fig. 3 is an end view, partly broken away and

partly in section, of the same and denotes by the dotted line 1—1 the section on which Fig. 1 is taken; Fig. 4 is a detached side elevation of one of the pistons of the engine; Fig. 5 is a central vertical transverse section 60 through the same; Fig. 6 is a detached front elevation, partly broken away, of the frame of engine cylinders, the latter radiating from a central hub, the face of which is shown; Fig. 7 is a detached face view of a 65 valve-chest which in use is placed against the face of the hub shown in Fig. 6; Fig. 8 is a vertical section of the same on the dotted line 8—8 of Fig. 7; Fig. 9 is a detached face view or elevation of a cap-plate which, when 70 in use, is secured against the face of the chest shown in Figs. 7 and 8; Fig. 10 is an edge view of the same; Fig. 11 is a detached face view of a cam plate intended for co-operation with the exhaust valve stems of the 75 engine; Fig. 12 is an edge view of the same; Fig. 13 is a side elevation of a portion of the engine shaft with the reversing lever thereon, and Fig. 14 is an enlarged detached sectional view of the cam intended for co-operation with the exhaust valve stems. 80

In the drawings, 15 designates an engine shaft to be driven from a rotary frame 16 keyed thereon and which is rotated from the pistons 17, 18 adapted to reciprocate within cylinders 19, 20 radiating from a hub 21 mounted upon said shaft 15 but not rotatable therewith, the hub 21 and cylinders 19, 20 always remaining stationary while the frame 16 and shaft 15 are rotatable. 90

The frame 16 comprises a hub 22, radial spokes 23 and a peripheral rim 24 within which, by means of bolts 25, is secured a plate 26 which has a circular outer edge fitting within the outer edge of the rim 24, as shown in Fig. 1, and a rectangular or polygonal central opening 27 (Figs. 2 and 3) which encompasses the pistons 17, 18 and cylinders 19, 20, said plate 26 being on the central vertical plane of said pistons and 95 cylinders. 100

The inner polygonal edge portions of the plate 26 are formed in both sides with corresponding grooves 28, and the outer ends of the pistons 17, 18 are bifurcated to straddle 105 said portions of said plate 26 and carry at their outer ends rollers 29 confined within said grooves 28 and inwardly from said outer ends, rollers 30 which engage the inner edges of said plate 26 defining the opening 110

27 therein. In the present instance the opening 27 in the plate 26 is formed with four equal sides, and I provide four pistons and four cylinders for acting on said plate 26 to drive the frame 16, each side of said opening being engaged by one piston.

The edge of each side of the opening 27 tapers slightly from its center toward its ends, and this feature of the construction is to enable the roller 30 of each piston to always follow said edge during the rotation of the frame 16. When opposite sections of the grooves 28 are at right angles to the pistons, as shown in Fig. 3, the rollers 15 29, 30 of the pistons respectively engage the walls of said sections and the adjacent inner edges of the opening 27, and when the frame 16 makes a partial rotation carrying said sections to, say, the angular or diagonal 20 position shown in Fig. 2, the rollers 30 would bind against the frame except for the tapering of the edges of the sides of the opening 27. The distance between the rollers 29, 30 is fixed, and as opposite sections 25 of the grooves 28 move from the right angular position shown in Fig. 3 to the diagonal position shown in Fig. 2 the vertical lines denoting the thickness of metal between the said groove-sections and the inner 30 adjacent edges of the opening 27 pass diagonally through the inner edges of the plate 26 and hence the situation requires either a tapering of the edges of the sides of the opening 27 or a like tapering of the sections 35 of the grooves 28 to enable the rollers 29, 30 to follow both the grooves and the edge of the opening 27 without binding against either. The final effect is that the plate 26 has an inner polygonal operative outline 40 or wall composed of equal straight sides for coöperation with pistons oppositely arranged in pairs, said outline being defined by the walls of the grooves 28 if they have straight sections, as shown, or by the edges 45 of the opening 27 if its sides are straight and the said groove sections tapered, and said outline or wall being shown in the drawings as a square or rectangle.

The pistons 17, 18 are suitably packed or 50 equipped with rings of usual character, and in the operation of the engine the upper and lower pistons 17 move outwardly within their cylinders 19 to draw in the motive fluid, while the right and left hand or horizontal pistons 18 travel outwardly within their cylinders under the force of an explosion, the upper and lower pistons and right and left hand pistons thus having corresponding strokes, one set of pistons being 55 drawn outwardly by the frame 16 to create suction and the other set of pistons being impelled outwardly to impart rotary motion to said frame. While one set of pistons move inwardly and expel the burned gases 60 from their cylinders, the other set of pis-

tons moving inwardly compress the fluid within their cylinders.

The cylinders 19, 20 may be formed integrally with the hub 21, and said cylinders in pairs communicate with one another, the upper and lower cylinders 19 being in communication with each other through vertical ports 31 and the horizontal cylinders being in communication with each other through ports 32, which ports are in the form of passages extending through the hub 21 at opposite sides of the bore for the shaft 15. The upper and lower cylinders 19 communicate at their inner ends with each other and the cylinders 20 at their inner ends communicate with each other, but the cylinders 19 do not communicate with the cylinders 20.

The shaft 15 is supported in a suitable bearing 33 from the engine bed 34 and also 85 by having a bearing in the valve chest 35, plate 36 and hub 21, which are supported from said bed. The frame 16 is in the nature of a fly-wheel.

The valve chest 35 is secured against the outer face of the hub 21, as shown in Fig. 1, and upon the outer face of the valve chest 35 is secured the plate 36 through which the valve stems, hereinafter designated, extend and which plate is provided with a suction port 37 for all of the cylinders and an exhaust port 38 for all of the cylinders (Figs. 9 and 10). The valve chest 35 is formed in its outer face with segmental chambers 39, 40, as shown in Figs. 7 and 8, and on its inner face with segmental chambers 41, 42, which correspond with the chambers 39, 40 but are set off therefrom, as the dotted lines for the chambers 41, 42 in Fig. 7 indicate. One end of the outer chamber 39 is connected by a port 43 with one end of the chamber 41, and the other end of the chamber 41 is connected with the chamber 40 by a port 44, and the other end of the chamber 40 is connected by a port 45 with one end of the inner chamber 42, whose other end is, by a port 46, connected with the chamber 39 at that end thereof opposite to the port 43. The outer plate 36 is formed with four nipples 47 which are respectively in line 115 with the ports 43, 44, 45, 46 and furnish bearings for the valve stems 48, 49 for the valves 150, 51 which control said ports 48, 44, 45, 46, said valve stems being provided on their outer ends with coiled springs 120 (Fig. 1) for normally seating said valves.

Around the suction and exhaust ports 37, 38 in the plate 36 are bushings into which the suction and exhaust pipes, not shown, will be screwed, as usual, the suction pipe 125 leading from any suitable carburetor. The inlet port 37 leads into the chamber 39 of the valve chest 35, and the exhaust port 38 leads from the chamber 40 in said chest. In the hub 21 which carries the cylinders are formed 130

two ports 50 (Fig. 6) one of which communicates at one end with the upper cylinder 19 and at its other end is in line with the port 43 in the chest 35, while the other port 50 is in communication at its inner end with the right hand cylinder 20 and at its outer end in line with the port 46 in said valve chest 35. The chamber 39 in the chest 35 is in communication, as hereinbefore explained, 10 with the inlet of suction port 37; and the ports 43, 46 connect said chamber 39 with the chambers 41, 42, whence the motive fluid may, at the proper time, pass into the respective ports 50 and thence enter the said 15 cylinders 19 or 20 as required. The valves which control the ports 43, 46 are suction valves and they close automatically under the force of their springs. The suction valves are not mechanically opened, but are 20 always controlled on the inlet of the motive fluid by the suction created by the outwardly moving pistons of the cylinders intended to receive such fluid. The valves for the ports 44, 45 are exhaust valves and they 25 are always mechanically operated to open by means of a cam 52 mounted on and rotating with the shaft 15. The ports 50 operate as both suction or inlet and exhaust ports, the suction taking place in through the upper 30 port 50 when the two vertical cylinders are to be supplied with the motive fluid and in through the lower port 50 when the two horizontal cylinders are to be supplied with the motive fluid, and the exhaust is through 35 the upper port 50 when the two vertical cylinders are to be cleared of the products of combustion and out through the lower port 50 when the horizontal cylinders are to be cleared of the products of combustion.

40 The cam 52 rotates with the shaft 15 and is formed with cam surfaces at its upper and lower ends to engage at the proper time the rollers carried on the outer ends of the exhaust valve-stems, these exhaust valves being 45 mechanically opened by the movement of the cam 52 against their stems. The cam 52 will be adjusted angularly on the shaft 15 in accordance with the direction of motion it is intended the engine shall have, and 50 this adjustment or setting of the cam 52 is accomplished by the movement of a reversing lever 53, a slide 54 connected therewith and arranged to move in a key-way 55 formed in the shaft 15, a pin 56 carried by 55 said slide, and a spiral groove 57 formed in the hub of the cam 52 in position to be engaged by said pin 56. By moving the lever 53, slide 54 and pin 56 in one direction, said pin will actuate the cam 52 to make a one- 60 eighth turn on the shaft 15 and thereby set the cam for opening the exhaust valves at the proper time under one direction of motion of the rotary frame 16; and by moving said lever 53, slide 54 and pin 56 in the opposite direction, the said pin will restore said

cam 52 to its initial position for opening the exhaust valves under an opposite direction of rotation of the frame 16.

As may be observed on reference to Figs. 1 and 2, all of the pistons 17, 18 move outwardly at one time; two opposite pistons then drawing in the motive fluid into their cylinders, while the other two opposite pistons are moving outwardly under the force of an explosion; when the latter set of pistons move inwardly they expel the burned gases from their cylinders, and at the same time the other set of pistons moving inwardly compress the fluid within their cylinders preparatory to an explosion.

If we assume that the upper and lower pistons 17, shown in Fig. 2, are moving outwardly, being drawn outwardly by the then rotating frame 16, to suck in motive fluid and that the two horizontal pistons 18 are moving outwardly under the force of an explosion, we will have the following conditions with respect to the valves and chambers of the valve chest 35: Since the upper and lower pistons 17 are moving outwardly to create suction, the inlet for motive fluid will be through the port 37 in the plate 36 to the chamber 39 in the outer face of the valve chest 35, thence through the port 43 (the valve of which was opened by the suction) into the chamber 41 and upper port 50 leading to the upper cylinder 19, whence the motive fluid will pass through the passages 31 to also supply the lower cylinder 19. The expansion of gas due to the explosion in the horizontal cylinders 20, by its force acts to keep the valve at the port 46 and also the valve at the port 45 closed; the expanded gas filling the lower port 50 and chamber 42 of the valve chest 35 and exerting pressure against the valves at said ports 46, 45. Under the conditions stated a suction may take place through the chamber 39, port 43, chamber 41 and upper port 50 into the upper and thence into the lower cylinder 19, while the ignited gases are expanding in the two horizontal cylinders 20.

Upon the in-strokes of all of the pistons, following the condition just above described, the upper and lower pistons 17 will compress their charges and the horizontal pistons 18 will clear their cylinders. During the inward movement of the upper and lower pistons 17 to compress their charges, the gases therein will act through the upper port 50 and chamber 41 against the valves at the ports 43 and 44 and maintain the same closed, so that there may be no outlet for the gases under compression and no communication from the cylinders 19 to the cylinders 20. During the inward movement of the pistons 18 to clear their cylinders, the burned gases are forced outwardly through the lower port 50 into the inner chamber 42 of the valve chest 35 and thence

through the port 45 into the outer chamber 40 of said chest and thence directly out through the exhaust port 38, the valve for the port 45 being opened to connect the chamber 42 with the chamber 40 by the action of the rotating cam 52 against the stem of said valve. When the upper and lower pistons 17 immediately thereafter move outwardly under the force of an explosion within their cylinders, they act to rotate the frame 16 and the expanded gases within them fill the upper port 50 and chamber 41 and maintain the valves at the ports 43, 44 closed.

15 While the upper and lower pistons are moving outwardly under the force of an explosion, they rotate the frame 16 and the latter draws the two horizontal pistons outwardly (they having cleared their cylinders) and this outward movement of said horizontal pistons creates suction for recharging their cylinders. The entrance for the motive fluid to the horizontal cylinders is through the inlet port 37, chamber 39, port 46, chamber 42 and lower port 50, which communicates directly with one of the cylinders 20, this cylinder being in communication with the other cylinder 20 by means of the passages 32 connecting them.

20 When following this outward movement of the pistons 17, 18 (the latter pistons move inwardly to compress), the gases under compression will fill the lower port 50 and chamber 42 and will act to firmly maintain the valves at the ports 46, 45 in closed position. During the inward movement of the upper and lower pistons 17 to clear their cylinders, the discharge will take place through the upper port 50, chamber 41, port 44 and chamber 40 of the valve chest, said chamber 40 having the exhaust port 38 connected with it. The exhaust from the series of ports and chambers just identified is permitted by the fact that the cam 52 at the proper time opens the valve for the port 44 so that the exhaust gases entering the chamber 41 may pass therefrom into the chamber 40 and thence escape through the port 38. The pistons 18 having moved inwardly to compress the charge and the pistons 17 having moved inwardly to clear their cylinders, an explosion will occur in the cylinders 20 to move the pistons 18 outwardly again, thereby to impart rotary motion to the frame 16, which will draw the pistons 17 outwardly to suck in an additional charge of the motive fluid. The inlet to and discharge from the upper and lower cylinders 19 and the inlet to and discharge from the horizontal cylinders 20 through the valve chest 43 have been fully explained above.

25 The engine will be provided with suitable sparking devices 58 for igniting the compressed charges at the proper time. The ignition takes place in the upper and lower ports 50, into which the spark-plugs extend, (Fig. 1). An explosion in the upper port 50 results in the expanded gases acting against both pistons 17, since as hereinbefore explained the cylinders 19 thereof are in communication with each other. An explosion in the lower port 50 results in the expanded gases passing into both of the horizontal cylinders 20, driving the pistons 18 thereof outwardly, since said cylinders 20 are in direct communication with each other.

30 The rotary frame 16 by reason of its polygonal opening 27 and the connection of the edge portions thereof with all the pistons, will have motion imparted to it by the opposite pistons moving outwardly under the force of an explosion and will at the same time draw the other opposite pistons outwardly to suck a charge of the motive fluid into their cylinders. The continued rotation of the frame 16 under the momentum imparted to it (moving from the position shown in Fig. 2 to that shown in Figs. 1 and 3) will force all the pistons inwardly, and thereupon an explosion will take place in two opposite cylinders and their pistons will be forced outwardly and impart further rotary force to the frame 16, which then moving to the position shown in Fig. 2 will draw the other two pistons outwardly on their suction strokes.

35 In the example of the invention illustrated the frame 16 has an opening 27 possessing four equal sides, and there are four pistons, one to always be in engagement with one of said sides, and four cylinders or said pistons. There are two inlet valves, one for the port 43 which supplies the upper and lower vertical cylinders, and one for the port 46 which supplies the horizontal cylinders; and there are two exhaust valves, one for the port 44 through which the products of combustion escape from the said vertical cylinders, and one for the port 45 through which the burned gases discharge from the said horizontal cylinders.

40 Since the opening 27 in the fly-wheel frame 16 has four equal sides, each rotation thereof will result in all the pistons being forced inwardly (Fig. 3) four times during such rotation, and since on each inward movement of said pistons an explosion occurs in two opposite cylinders to drive their pistons outwardly to rotate said frame 16 (Fig. 2), there will be four explosions during each rotation of the frame 16 and the latter will receive four impulses during each of its rotations.

45 The inward movement of the pistons occurs during about one-eighth of a rotation of the fly-wheel frame 16 or while the said frame is turning from its position shown in Fig. 2 to that shown in Figs. 1 and 3, and the outward movement of the pistons takes

125

130

place while the frame 16 is making a further one-eighth rotation or turning from the position shown in Fig. 2 to that illustrated in Fig. 3; and it is to be noticed that the 5 sides of the opening 27 move toward a position at right angles to the longitudinal planes of the respective pistons when driving said pistons inwardly, and that during the outward movement of the pistons said 10 sides move toward an angle of forty-five degrees thereto, thus enabling the pistons which are moving outwardly under the force of an explosion to exert their power against the fly-wheel frame at such angles as to 15 cause the latter to rotate.

On the starting of the engine, the fly-wheel frame 16 should be turned about one-quarter stroke by hand.

Should it be desired to reverse the engine, 20 the cam 52 should be set back about one-eighth turn so that it may operate to open the exhaust valves in proper timing.

I do not confine my invention to an engine comprising a frame 16 having four 25 equal sides and to the employment therewith of four pistons, since in the foregoing description I have only meant to comply with the law in presenting a detailed description of the best embodiment of the invention at 30 present known to me. Obviously the opening 27 may have six or more equal sides without necessarily increasing the number of pistons and cylinders, if it should be desired to increase the number of impulses imparted to the frame 16 during each of its 35 rotations. The engines may also be used in duplicate on the same shaft if desired, and when so duplicated I recommend that a set 40 of the pistons of one engine be timed to act on their rotary frame the moment a set of pistons of the other engine cease to act on the rotary frame of their engine. Under this timing of the pistons of the respective engines there would be no possibility at any 45 time of a dead center. When one engine only is on the shaft, momentum is depended on to prevent dead centering.

What I claim as my invention and desire 50 to secure by Letters Patent, is:

1. An engine comprising a shaft to be driven, a rotary driving frame connected therewith having a polygonal opening and affording a polygonal bearing surface, a series 55 of pairs of oppositely arranged stationary cylinders, pistons in said cylinders having outwardly extending portions, means slidably connecting the outwardly extending portions of opposite pistons with relatively similar portions of said frame and the polygonal bearing surface afforded thereby, whereby during the rotation of said frame all of said pistons will move outwardly and inwardly in unison, and suitable inlet and exhaust port connections arranged to enable one pair of opposite pistons 60

tons on their outward stroke to suck in the explosive mixture and another pair of opposite pistons, due to the explosion in the cylinders confining them, to move outwardly and impel said frame and whereby when all 70 said pistons are pressed inwardly by said frame the said suction pistons compress their mixture and said impelling pistons exhaust their cylinders; substantially as set forth. 75

2. An engine comprising a shaft to be driven, a rotary driving frame connected therewith and having a polygonal opening and in opposite faces continuous grooves extending along said opening, a series of pairs 80 of oppositely arranged stationary cylinders, pistons in said cylinders having outwardly extending portions, rollers carried on the outwardly extending portions of said pistons and respectively engaging the edge of 85 said opening and extending into said grooves and thereby connecting the opposite pistons with relatively similar portions of said frame, whereby during the rotation of said frame all of said pistons will move outwardly and inwardly in unison, and suitable inlet and exhaust port connections arranged to enable one pair of opposite pistons on their outward stroke to suck in the explosive mixture and another pair of opposite pistons, due to the explosion in the cylinders confining them, to move outwardly and impel said frame and whereby when all 90 said pistons are pressed inwardly by said frame the said suction pistons compress their mixture and said impelling pistons exhaust their cylinders; substantially as set forth. 95

3. An engine comprising a shaft to be driven, a rotary driving frame connected therewith having a substantially rectangular equal-sided opening and affording a continuous bearing surface, a series of pairs of oppositely arranged stationary cylinders, pistons in said cylinders having outwardly extending portions, means slidably connecting the outwardly extending portions of said pistons with relatively similar portions of said frame and the polygonal bearing surface afforded thereby, whereby during the rotation of said frame all of said pistons 105 will move outwardly and inwardly in unison, and suitable inlet and exhaust port connections arranged to enable one pair of opposite pistons on their outward stroke to suck in the explosive mixture and another 110 pair of opposite pistons, due to the explosion in the cylinders confining them, to move outwardly and impel said frame and whereby when all said pistons are pressed inwardly by said frame the said suction pistons compress their mixture and said impelling pistons clear their cylinders; substantially as set forth. 115

4. An engine comprising a shaft to be driven, a rotary frame connected therewith 120

for driving the same and having bearing surfaces defining a continuous polygonal outline concentric with said shaft, a series of pairs of radial stationary cylinders in communication with each other in pairs at their inner ends and a cylinder of each pair having a port 50 which serves as an inlet and exhaust port, pistons in said cylinders having outwardly extending portions, and 10 means slidably connecting said outwardly extending portions of said pistons with said frame and said bearing surfaces, combined with a chest having in one side chambers 39, 40, in its opposite side chambers 41, 42, ports 15 43, 46 and 44, 45 connecting said chambers 39, 40 respectively at their ends with the ends of the chambers 41, 42, a suction port 37 leading into the chamber 39 and an exhaust port 38 leading from the chamber 40, 20 suction-valves for the ports 43, 46 and exhaust-valves for the ports 44, 45, the said inlet-and-exhaust port for one pair of cylinders being in line with the port 43 connecting the chambers 39, 41 and the one for the 25 other pair of cylinders being in line with the port 46 connecting said chambers 39, 42; substantially as set forth.

5. An engine comprising a shaft to be driven, a rotary frame connected therewith 30 for driving the same and having bearing surfaces defining a continuous polygonal outline concentric with said shaft, a series of pairs of cylinders and pistons radially disposed with respect to said shaft for driving 35 said frame, means slidably connecting outwardly extending portions of said pistons with relatively similar portions of said bearing surfaces, whereby during the rotation of said frame all of said pistons will move outwardly and inwardly in unison, and suitable inlet and exhaust port connections arranged to enable one pair of opposite pistons on their outward stroke to suck in the explosive mixture and another pair of opposite pistons, due to the explosion in the cylinders 40 confining them, to move outwardly and impel said frame and whereby when all said pistons are pressed inwardly by said frame the said suction pistons compress their mix- 45

ture and said impelling pistons exhaust 50 their cylinders; substantially as set forth.

6. An engine comprising a shaft to be driven, a rotary frame connected therewith for driving the same and having bearing surfaces defining a continuous polygonal outline concentric with said shaft, a series of pairs of cylinders and pistons radially disposed with respect to said shaft for driving 55 said frame, and means slidably connecting outwardly extending portions of said pistons with said bearing surfaces, said cylinders being stationary and provided with suitable inlet and exhaust ports and valves, combined with a cam on said shaft for opening the exhaust valves, means for turning 60 said cam for setting it to open said exhaust valves on a reversal of the engine, and springs for closing said inlet and exhaust valves.

7. An engine comprising a shaft to be 70 driven, a rotary frame connected therewith for driving the same and having bearing surfaces defining a continuous polygonal outline concentric with said shaft, a series of pairs of cylinders and pistons radially disposed with respect to said shaft for driving 75 said frame, and means slidably connecting outwardly extending portions of said pistons with said bearing surfaces, said cylinders being stationary and provided with 80 suitable inlet and exhaust ports and valves, combined with a cam on said shaft for opening the exhaust valves, means for turning 85 said cam for setting it to open said exhaust valves on a reversal of the engine, and 90 springs for closing said inlet and exhaust valves, said means for turning the cam comprising a slide set in said shaft and carrying a stud, a spirally walled groove formed in the hub of said cam to receive said stud, and a lever for operating said slide.

Signed at New York, in the county of New York, and State of New York, this 1st day of April A. D. 1908.
